UNITED STATES PATENT OFFICE

106,233

DESIGN FOR A LABEL

Clark H. Hogan, Oklahoma City, Okla.

Application January 18, 1937, Serial No. 67,119

Term of patent 3½ years

To all whom it may concern:

Be it known that I, Clark H. Hogan, a citizen of the United States, residing at Oklahoma City, in the county of Oklahoma and State of Oklahoma, have invented a new, original, and ornamental Design for a Label, of which the following is a specification, reference being had to the accompanying drawing, forming part thereof.

The figure is a plan view of a label, showing my design.

I claim:

The ornamental design for a label, as shown.

CLARK H. HOGAN.
